Oct. 28, 1884

UNITED STATES PATENT OFFICE.

HENRY TEXTOR, OF BROOKLYN, NEW YORK, ASSIGNOR TO J. S. & G. F. SIMPSON, OF SAME PLACE.

DESIGN FOR A NEWEL-POST.

SPECIFICATION forming part of Design No. 15,503, dated October 28, 1884.

Application filed August 26, 1884. Term of patent 7 years.

To all whom it may concern:

Be it known that I, HENRY TEXTOR, of Brooklyn, in the county of Kings and State of New York, have originated a certain new and useful Design for Newel-Posts, of which the following is a specification.

I will describe in detail a newel-post embodying my design, and then point out the characteristic features of the design in the claim.

10 The accompanying illustration is a perspective view of a newel-post embodying the design.

A designates the base of the newel. B designates the body. C designates the cap. D designates the finial. The base A is shown as of rectangular form. At the top it is provided with a molding, a. The body is polygonal. Above the molding a is a flat-sided portion, b, embellished with corrugated ornaments b'. The flat-sided portion b is surmounted by a molding, b'', and above the molding b'' are foliate ornaments b''. Above the foliate ornaments b'' is a molding, b''. In the sides of the body B are panels b'', embellished with foliate figures b''. Above the panels b'' bars

b' extend around the body. Moldings b'' extend around the body above the bars b''. Above the moldings b'' is a flat-sided portion, b'', from which extend downwardly V-shaped projections b''. These V-shaped portions are embellished with rosettes b''. The flat-sided portion b'' is surmounted by a foliate molding, b''. The cap C of the newel has moldings c' and c''. The finial D has a circular rounding base, d, surrounded by an upwardly-tapering portion, d'. Above the portion d' is a molding, d'', surrounded by a bowl-shaped urn, d'', having a fluted lower portion, d'', circumferential moldings d'', a bell-shaped upper portion, d'', and a superposed knob, d'', ornamented with moldings d''.

What I claim as my invention, and desire to secure by Letters Patent, is—

In a design for a newel-post, the body thereof shaped and ornamented substantially as shown.

H. TEXTOR.
